UNITED STATES PATENT OFFICE.

SILAS E. BUTLER, OF TOLEDO, OHIO, ASSIGNOR TO THE GROSS PHOTO SUPPLY COMPANY, OF TOLEDO, OHIO, A CORPORATION OF OHIO.

CORNER-HOLDER FOR PHOTOGRAPHS OR THE LIKE.

1,356,693.

Specification of Letters Patent. Patented Oct. 26, 1920.

Application filed May 15, 1919. Serial No. 297,428.

To all whom it may concern:

Be it known that I, SILAS E. BUTLER, a citizen of the United States, and a resident of Toledo, in the county of Lucas and State of Ohio, have invented a certain new and useful Corner-Holder for Photographs or the like; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to corner-holders for photographs, cards or the like, and has for its object the provision of simple and improved means of this character which is inexpensive and strong and durable in its construction and is easy of application to a card or the like.

The invention is fully described in the following specification and while in its broader aspect it is capable of embodiment in numerous forms, a preferred embodiment thereof is illustrated in the accompanying drawings, in which,—

Figure 1 is a face view of a corner-holder embodying the invention attached to a card. Fig. 2 is a rear view thereof. Fig. 3 is a section on the line 3—3 in Fig. 1. Fig. 4 is a view of a holder removed from the card and in open position. Fig. 5 is a face view of a slightly modified form of the holder attached to a card. Fig. 6 is a view thereof removed from the card and in open position, and Figs. 7 and 8 are face views of different modifications of the holder, with each attached to a card.

Referring to the drawings, 1 designates a backing card or mount for a photograph, and in Fig. 1 it is shown as having a slit 2 provided diagonally in a corner portion thereof. The corner holder embodying the preferred form of the invention comprises a single strip 3 of any suitable material, such, for instance, as a heavy piece of paper of a tough nature, but preferably of celluloid to render the holder transparent. The strip 3 is of elongated rectangular form and has each end portion stamped or slit to form an inwardly projecting tongue 4. In form-

ing the holder the opposite ends of the strip 3 are folded toward each other along diagonal lines 5 so as to place such ends in parallel relation transverse to the body of the strip with their inner edges preferably substantially meeting so that the strip forms a triangular pocket 6 adapted to receive the corner of a photograph, card or the like. The end portions of the strip project beyond the open side of the pocket thus formed and are intended to be projected through the slit 2 in the mount or backing card 1, as shown in Figs. 1, 2 and 3. The tongues 4 are so disposed that they are adapted to engage the outer wall of the slit 2 when the strip ends are inserted in the slit and to coact with said wall to prevent a withdrawal of the strip ends, as best shown in Fig. 2.

It is evident that the strip 3 forming the holder may be quickly and easily folded into its triangular corner holding shape and the projected ends thereof inserted through the slit 2 and their tongues 4 engaged to a wall of the slit to prevent withdrawal.

The form of the invention illustrated in Figs. 5 and 6 is slightly modified from that above described as its pocket is illustrated as receiving a corner of the backing card and the ends of the strip, which lie at the back of the card 1, have outwardly projecting tongues 7, which are turned inwardly through openings 8 in the card and bent in hooked form around the outer wall thereof to prevent an outward withdrawal of the holder from engagement with the card. The material from which the holder is formed should be sufficiently stiff for the tongues 7 thereof to maintain their bent or hooked engagement with the walls of the card openings 8.

In the modification illustrated in Fig. 7 the ends of the strip are extended through a diagonally disposed corner slit 2 of the card, but instead of having tongues for engagement with a wall of the slit to prevent withdrawal of the strip ends therefrom, the strip ends are bent back to have hooked engagement with the slit wall, as shown at 9.

In Fig. 8 the card 1 is provided with two spaced parallel slits 2 and the strip ends, which project beyond the holder pocket are made of sufficient length to be projected rearwardly through the first or outer slit 2

and are then extended forwardly through the inner slit 2 with the portions thereof which are projected through the latter slit bent outward toward the holder pocket and 5 lying substantially flat against the card.

It is evident that in each form of the invention illustrated the holder is composed of an elongated strip with the end portions thereof turned into parallel relation along 10 diagonal converging lines so that the end portions are disposed in substantially parallel relation and coöperate with the body portion of the strip disposed between the fold lines to form a triangular corner-receiving 15 pocket for a card, photograph or the like. It is also evident that in each form of the invention the folded end portions of the strip have their outer ends projected transversely beyond the open side or mouth of 20 the corner receiving pocket and are engaged in one manner or another with the backing card 1 to retain the corner-holder in engagement therewith. It is found in practice that celluloid is the best material to 25 use for the purpose as it is not only of sufficient stiffness to adapt it for the purpose but its transparency makes it particularly practicable for use as a corner-holder for photographs. It is understood, how- 30 ever, that while celluloid is preferably used, the invention is not restricted to the use of the same or to any other particular material.

I wish it understood that my invention is 35 not limited to any specific construction, arrangement or form of the parts, as it is capable of numerous modifications and changes without departing from the spirit of the claims.

40 Having thus described my invention, what I claim as new and desire to secure by Letters Patent, is,

1. A corner-holder of the class described, comprising an elongated strip of sheet material having its opposite end portions folded toward each other along converging diagonal lines to coöperate with the body of the strip to form a diagonal pocket, the outer end terminals of said end portions being projected beyond the mouth portion of 50 the pocket and having card engaging tongues integral therewith.

2. The combination with a backing card, having a slit therein, of an elongated strip 55 of sheet material having end portions folded toward each other along converging diagonal lines to place the end portions in substantially parallel relation to coöperate with the strip body to form a diagonal pocket, the terminals of said end portions being projected through the card slit and having integral tongues provided thereon 60 for interengaging with the wall of the slit

to prevent withdrawal of the strip ends therefrom.

3. A corner-holder of the class described, comprising an elongated strip of sheet material having its opposite end portions folded toward each other along converging diagonal lines to coöperate with the body 70 of the strip to form a diagonal pocket, the outer end terminals of said end portions being projected beyond the mouth portion of said pocket and having tongues struck therefrom.

4. The combination, with a backing card, of a corner-holder attached thereto and comprising an elongated strip of sheet material with the opposite end portions thereof bent toward each other along diagonal 80 converging lines, to coöperate with the body of the strip to form a corner receiving pocket, with the terminals of the end portions projecting beyond the open side thereof and provided with tongues which inter- 85 engage with said card to retain the holder in engagement therewith.

5. The combination, with a card having a slit therein, of an elongated strip of sheet material having its opposite end portions 90 bent toward each other along diagonal converging lines to coöperate with the body portion of the strip to form a pocket, with the terminals of the end portions projecting beyond the open side of the pocket and through the card slit and interengaging 95 with a wall of said slit to prevent withdrawal of the strip ends therefrom.

6. The combination, with a backing card having a slit therein, of an elongated strip 100 of sheet material having end portions folded toward each other along converging diagonal lines to place the end portions in substantially parallel relation to coöperate with the strip body to form a triangular pocket, 105 with the terminals of said end portions extended beyond the open side of the pocket through the card slit and having tongues formed therein for interengaging with a wall of the slit to prevent withdrawal of 110 the strip ends therefrom.

7. A corner-holder of the class described comprising an elongated strip of sheet celluloid having its end portions folded toward each other along converging diagonal 115 lines to place them in substantially parallel relation and to coöperate with the body portions of the strip to form a triangular corner receiving pocket, with the terminals of said end portions projecting beyond the open side of the pocket and having portions bent to prevent withdrawal thereof from an opening in which inserted.

In testimony whereof I have hereunto signed my name to this specification.

SILAS E. BUTLER.
